PAPER-FINGER.

1,310,829.

Specification of Letters Patent. Patented July 22, 1919.

Application filed July 8, 1918. Serial No. 243,823.

To all whom it may concern:

Be it known that we, OTTO A. HOKANSON and ALFRED O. H. EBERT, citizens of the United States, residing at Woodstock, in 5 the county of McHenry and State of Illinois, have invented certain new and useful Improvements in Paper-Fingers, of which the following is a specification.

This invention relates to the means for 10 holding paper, or other material to be printed against the platen of a typewriter, and the principal object of the invention is to provide a new and improved construction by which the material to be printed or 15 written upon will be held yieldingly against the platen in either upper or lower case position, the paper finger being so pivoted that it can be withdrawn from contact with the platen for erasure or manipulation of the 20 paper beneath the paper finger, but can only be held away from the platen by manual attention thereto. Other objects of the invention will appear hereinafter.

The invention consists in the novel construction, combination and arrangement of the several parts.

In the accompanying drawing—

Figure 1 is a front elevation of a pair of paper fingers mounted at the front of a 30 typewriter platen.

Fig. 2 is a sectional view taken on line 2—2 of Fig. 1.

Fig. 3 is a rear view of one of the paper fingers; and

Fig. 4 is a plan view of a portion of a paper finger when it is rotated forwardly in the broken line position as shown in Fig. 2.

It is desirable that a paper finger shall 40 exert sufficient pressure upon the typewriter platen to hold the paper, or other material firmly against the platen in all positions, and it is also desirable that the paper finger may be of such construction that it can be 45 withdrawn from contact with such material as desired without rotating or moving the platen. In the present invention a pivoted paper finger is provided which has an engaging spring tongue so disposed that the 50 paper finger is held yieldingly against the platen, and the tongue is provided with engaging portions which prevent the paper finger proper from being rotated to such a

position that the spring tongue will not return it to contact with the platen. This insures that the finger of the operator must be held upon the paper finger to hold it away from the platen. 55

Referring now more particularly to the drawing, a space bar 1 is fixed in front of and below a rotatable and vertically shiftable platen 2, and in front of the platen is a shiftable line finder 3 which moves vertically with the platen and is guided in its vertical movement by studs 4 which project 60 rearwardly from some parts, such as the type bar segment (not shown) in front of the line finder.

Slidable on the bar 1 are two paper fingers, one on each side of the line finder 3, 70 and each paper finger comprises a slidable portion 5 which has the upper and lower edges 6 and 7 bent over the front edge at the top and bottom of the bar, respectively, so that they do not cover the graduated face 75 8 of the bar, which is preferably extended beyond the upper and lower edges. This slidable portion 5 is also formed with an up-standing central tongue 9 which has a recess 10 in its upper edge and with pivoting portions 11, in which a pivot pin 12 is mounted.

Mounted on the pivot pin 12 is the rotatable portion 13 of the paper finger which comprises a central integral tongue 14 with a reduced portion 15 near the free end 85 adapted to enter the recess 10 and with projections 16 at the end of this reduced portion 15 for engaging the sides of the fixed tongue 9 which form the recess 10 so that when the rotatable portion 13 is bent forwardly, as shown in Fig. 2, the projections 16 of the tongue 14 will engage the sides of the recess 10, as shown more clearly in Fig. 4. At the upper end of the paper finger a bearing roller 17 is mounted in a recess and 95 the upper extremity 18 is turned outwardly from the platen to form an engaging finger hold portion. The outer side of each paper finger is provided with a projection 19 which is adapted to engage the outer edge 100 of the line finder 3, as indicated in Fig. 1, so that neither paper finger can be moved inwardly to cover an opening 20 at the center of the line finder, or to cover the printing point, which is substantially at the center 105 of this opening on a line with the gradu-

ated edge 21 thereof. The outer edges 22 of the line finder are bent outwardly from the platen 2 so that the paper fingers will readily slide under the line finder, but neither 5 one of them can be moved inwardly to cover the printing point because of the engagement of its projection 19 at the outer side of the line finder which is guided in its vertical movement by the studs 4 which also prevent 10 the engagement of the paper fingers from disturbing lateral alinement or position of the line finder.

It will be observed that the spring tongue 14 by its engagement with the spring 15 tongue 9 of the slideable portion of the paper finger prevents the forward movement of the rotatable portion of the paper finger beyond the position where it will be returned to again contact with the platen which insures 20 that the paper finger must be manually held in its forward position, and that as soon as the manual pressure is relieved, it will be returned to again contact with the platen.

25 We claim:

1. A paper finger having a slideable member, and a pivoted member with an integral spring tongue which normally engages the slideable member for pressing the pivoted member in one direction from the slideable member and also with a portion which limits manual movement of the pivoted member in the other direction so that the pivoted member is always returned by the 30 spring tongue in the first-mentioned direction as soon as the manual engagement is released.

2. A paper finger having a slideable member with an upstanding projection, and a 40 portion pivoted thereto having an integral spring tongue to engage the projection, tending to press the portion away from the member in one direction, the tongue and projection having inter-engaging means for 45 limiting the movement of the pivoted portion in the other direction and for immediately returning the member in the first-named direction when manually released from the limiting position.

50 3. A paper finger having a slideable member with an upstanding resilient projection, and a portion pivoted thereto having an integral spring tongue adapted to engage the projection for limiting the movement of the pivoted portion in one direction so that this pivoted portion will always be returned by the resilient engagement of the parts.

60 4. A paper finger having a member with an upstanding projection, and a portion pivoted thereto with a spring tongue normally engaging the rear of the projection for holding the pivoted portion in predetermined position, the pivoted portion being manually rotatable forwardly to engage the 65 spring tongue with the top of the said projec-

70 jection for limiting the movement of the pivoted portion in the forward direction and for always returning it to the predetermined position as soon as released from manual engagement.

5. A paper finger having a member with an upstanding resilient projection of which the upper edge is formed with a recess, and a portion pivoted to the member having an integral spring tongue normally engaged 75 the rear of the projection but having a reduced portion adjacent the end of the tongue with an enlarged portion at the end adapted to engage the recess at the upper end of the projection to limit the movement 80 of the pivoted portion in a forward direction.

6. A paper finger having a member with an upstanding spring tongue having a recess at its upper edge, and a member pivoted to 85 the first member with an integral spring tongue having a reduced portion adjacent the free extremity thereof to engage in the recess at the top of the projection only when the finger is rotated forwardly, the engagement of the spring tongue with the spring projection serving always to return the pivoted member from its forward position.

7. In a typewriter, a platen and a bar in front of and below the platen, a paper finger having a portion slideable on the bar and another portion pivoted in the slideable portion, both of said paper finger portions having spring tongues which contact with each other to press the pivoted portion against the platen, the spring tongues being provided with inter-engaging means to limit the manual movement of the pivoted portion away from the platen and always to return it to engage the platen when released 100 from manual engagement.

8. In a typewriter, a platen and a bar in front of and below the platen, a paper finger having a portion slideable on the bar, and another portion pivoted in the slideable portion, both of said paper finger portions having spring tongues which contact with each other to press the pivoted portion against the platen, the spring tongues being provided with interengaging means to limit the 110 movement of the pivoted portion away from the platen and to automatically return the pivoted portion to contact with the platen after being manually rotated free from engagement therewith.

115 9. The combination with a platen and a bar disposed below and at the front of the platen, of a paper finger comprising a portion slideable on the bar having an upright spring projection with a recess in its upper 125 edge, and a portion pivoted to the slideable portion having an integral spring tongue the free end of which is formed with a reduced portion near the end, the spring tongue normally engaging the rear side of the projec- 130

tion for pressing the pivoted portion against the platen and the said reduced portion engaging in the recess of the said projection for limiting the forward rotation of the 5 pivoted portion and for always returning the pivoted portion to contact with the platen.

10. The combination with a platen and a bar at the front of and below the platen, 10 both transversely reciprocable; of a vertically movable line finder, with a guide for holding it against lateral movement and a paper finger having a portion slidable on the bar and another portion pivoted to the slidable 15 portion with a projection at one side of the pivoted portion, the pivoted and slidable

portions of the paper finger having inter-engaging spring portions for limiting the forward pivotal motion and to return the pivoted portion to contact with the platen, 20 and the projection from the pivoted portion being adapted to engage the outer edge of the line finder for preventing the movement thereof over the printing point at the center of the line finder due to the transverse movement of the platen and the bar upon which the line finder is mounted. 25

In testimony whereof we have signed our names to this specification on this 28th day of June, A. D. 1918.

OTTO A. HOKANSON.
ALFRED O. H. EBERT.
